C. EARNER

ELECTRIC TORCH

Filed, May 3, 1926

Inventor
C. Earner,
By Clarence O'Brien
Attorney

UNITED STATES PATENT OFFICE.

CHARLES EARNER, OF RAWLINS, WYOMING.

ELECTRIC TORCH.

Application filed May 3, 1926. Serial No. 106,468.

My present invention has to do with electric illuminating devices, and it contemplates the provision of an electric torch adapted to throw light in all directions from the bulb 14 of the incandescent electric lamp, and this, by preference, by the use of certain elements in combination with other elements common to the conventional electric flash light.

Other objects and practical advantages of 10 the invention will be fully understood from the following description and claims when the same are read in connection with the drawing, accompanying and forming part of this specification, in which:

15 The figure is a view partly in elevation and partly in diametrical section illustrative of the torch constituting the preferred embodiment of my invention.

In the preferred embodiment of my invention I employ a cylindrical casing 1 of the same general form as the casing body of an ordinary flash light, the said casing 1 being equipped with a switch 2 of the ordinary type or of any other approved construction compatible with the purpose of my invention, and being exteriorly threaded at one end as indicated by 3.

In the casing 1 is a battery 4, preferably of ordinary type, and provided with a central end terminal 5, and also in the casing 1 is a grounding terminal 6 which extends in the usual manner to the end of the casing 1 as designated by 7. A conductive collar 8 is threaded on the end of the casing 1 and has a flange portion 9 in contact with the terminal 6, and threaded on the said collar 8 is an exterior collar 9*, flanged at 10. A conductive disk 11 is arranged on the flange portion 9 of the collar 8 and fixed to the disk 11 and surrounding a central aperture therein a tubular post 12, threaded at its outer end as designated by 13 so as to serve as a socket for a conventional incandescent electric lamp designated by 14. Appropriately fixed in the inner end of the tubular post 12 and occupying the mentioned central aperture in the disk 11 is an insulating plug 15 and arranged in the said plug 15 is a conductor element 16 which is designed to contact at one end with the terminal 5 of the battery 4 and at its opposite end with the terminal 17 at the inner end of the lamp 4, it being understood in this connection that the filament of the lamp 14 is in electric connection with the tubular post 12 which is of conductive quality, so that from the fila-

ment of the lamp 14 the current will pass through the post 12, the disk 11, the flange of the collar 8, and the terminal 6.

At 18 is the transparent hood, of my improvement, the said transparent hood 18 being preferably of molded glass and cylindrical in form with its outer end closed and with a flange 19 at its inner end interposed between the flange 10 of the collar 9* and the disk 11.

The lamp 14 of my improvement is controlled through the medium of the switch 2 in the manner common to ordinary electric flash lights, and it will therefore be understood that the gist of my invention resides in the employment of the tubular post 12 with the lamp 14 at its outer end, and the transparent hood 18 resting outwardly beyond the lamp and entirely surrounding the lamp 14 and the post 12, this in order that light will be thrown from the bulb of the lamp 14 in all directions from the said bulb, that is to say, longitudinally outward and also laterally and entirely about the bulb 14 so that the torch may be held for the illumination of objects at the side of the torch as well as objects opposite the end of the torch. It will also be appreciated that the globe or hood 18 of molded glass will afford adequate protection to lessen the liability of the globe 14 being broken in use, the said hood 18 being possessed of the quality of a fender so that the hood 18 may be thrust into open portions of machinery without liability of any portion coming into contact with the globe 14.

It will be apparent from the foregoing that the major portion of a flash light may be employed in the fabrication of my novel electric torch, and therefore, when deemed expedient a flash light of conventional type may be expeditiously and easily converted into an electric torch adapted to utilize the bulb 14 of the incandescent electric lamp for the illumination of objects disposed about the said bulb 14.

It will further be apparent that my improvement is extremely simple and inexpensive in construction, and with renewal of the battery 4 at intervals, the device is adapted to last and to be used to advantage for an indefinite period of time.

I have specifically described the present and preferred embodiment of my invention in order to impart an exact understanding of the said embodiment in all of its details.

I do not desire, however, to be limited to the precise construction and arrangement of elements as shown and described, my invention being defined by my appended claims within the scope of which modifications may be made without departure from my invention.

Having described my invention, what I claim and desire to secure by Letters Patent, is:—

1. In combination, a casing, a disk of conductive character arranged in opposed relation to one end of the casing and having a central aperture and also having an outwardly extending tubular post fixed to it and surrounding said aperture, an incandescent electric lamp detachably secured in the outer end of said tubular post, a plug of insulating material disposed in the inner end portion of said tubular post, a conductive element terminating at the inner end of said plug and adapted to make contact at its outer end with a filament terminal at the inner end of the incandescent electric lamp,
2. In combination, a hood of transparent material closed at its outer end and surrounding the lamp and the tubular post and having at its inner end a flange opposed to the said conductive disk, a collar secured on the casing and having a flange opposed to the outer side of the flange on the hood, means in the casing for supplying current to the said conductive element in the tubular post being in the form of a dry battery disposed in the casing and having a terminal in contact with the inner end of the said conductive element, and the same means for grounding the current from the filament of the lamp being in the form of a terminal disposed in the casing and electrically connected with the said conductive disk.
3. In combination, a conductive disk having a central aperture, a tubular conductive post fixed to and extending from said disk and surrounding the aperture therein, an incandescent electric lamp detachably secured in the outer end portion of said post, a dielectric plug secured in the inner portion of said post, a conductive rod-like element extending through the dielectric plug and the post and contacting at its outer end with one terminal of the filament of the lamp, said rod-like element adapted at its inner end to contact with one terminal of a battery, a transparent hood closed at its outer end and surrounding the lamp and the tubular post, and having a flange at its inner end opposed to said conductive disk, and a collar having an inwardly directed flange surrounding the hood and resting at the outer side of the flange of the hood.

er end with a filament terminal at the inner end of the incandescent electric lamp, a hood of transparent material closed at its outer end and surrounding the lamp and the tubular post and having at its inner end a flange opposed to the said conductive disk, a collar secured on the casing and having a flange opposed to the outer side of the flange on the hood, means in the casing for supplying current to the said conductive element in the tubular post being in the form of a dry battery disposed in the casing and having a terminal in contact with the inner end of the said conductive element, and the same means for grounding the current from the filament of the lamp being in the form of a terminal disposed in the casing and electrically connected with the said conductive disk.

3. In combination, a conductive disk having a central aperture, a tubular conductive post fixed to and extending from said disk and surrounding the aperture therein, an incandescent electric lamp detachably secured in the outer end portion of said post, a dielectric plug secured in the inner portion of said post, a conductive rod-like element extending through the dielectric plug and the post and contacting at its outer end with one terminal of the filament of the lamp, said rod-like element adapted at its inner end to contact with one terminal of a battery, a transparent hood closed at its outer end and surrounding the lamp and the tubular post, and having a flange at its inner end opposed to said conductive disk, and a collar having an inwardly directed flange surrounding the hood and resting at the outer side of the flange of the hood.

In testimony whereof I affix my signature.

CHARLES EARNER.
